UNITED STATES PATENT OFFICE.

SAMUEL S. RIEGEL, OF SCRANTON, PENNSYLVANIA, ASSIGNOR TO PATTERSON-ALLEN
ENGINEERING COMPANY, A CORPORATION OF NEW YORK.

STEAM-DISTRIBUTING HEAD.

1,110,647.

Specification of Letters Patent. Patented Sept. 15, 1914.

Application filed May 28, 1914. Serial No. 841,423.

To all whom it may concern:

Be it known that I, SAMUEL S. RIEGEL, a citizen of the United States, and resident of Scranton, county of Lackawanna, and 5 State of Pennsylvania, have invented an Improvement in Steam-Distributing Heads, of which the following is a specification.

My invention has reference to a steam distributing head or casing and consists of certain improvements which are fully set forth 10 in the following specification and shown in the accompanying drawings which form a part thereof.

The object of my invention is to provide 15 a steam distributing head for use in connection with boilers by means of which steam may be distributed from a common point to several points of use, said distribution being controlled by a novel type of 20 valve mechanism for effecting the discharge of steam to any particular point of use.

It has for a further object to provide a 25 valve mechanism, all parts of which including the control devices therefor are removable as a unit from the aforesaid distributing head whereby the valve device may be readily replaced, repaired, or readjusted with minimum expense and with a great saving of time.

As a further object my invention provides 30 a means for supplying steam to a number of points of use from a common point of supply, the said points being selective at will and according to requirements.

My invention also comprehends details of 35 construction which, together with the features above specified, will be better understood by reference to the drawings, in which:—

Figure 1 represents a plan of the fire box 40 portion of a locomotive showing the steam distributing head of my invention; Fig. 2 represents a side elevation of the same; Fig. 3 represents a plan partly in section of the 45 distributing head on an enlarged scale; Fig. 4 represents a section on line $\alpha-\alpha$ of Fig. 3; Fig. 5 represents an end elevation of one of the valve devices showing a modified structure.

1 designates a casing or box-like structure 50 which I have, for convenience, termed a

steam distributing head, consisting of a suitable shaped casting shown here as substantially triangular in plan, and provided with flat surfaces or bosses 2 at suitable locations 55 in order to permit the mounting of the different valve structures which will be presently described. The head casing 1 is provided with an inlet opening 3 preferably, though not necessarily, located at an apex 60 of the triangle and a flange 4 by which connection is made to the main control valve member 5 located in the steam supply pipe 6 leading from the steam space of the boiler. In the preferred embodiment of the invention 65 the distributing head or casing is mounted directly upon the fire box portion 7 of a locomotive boiler and adjacent the rear end thereof so that the operating levers or means for manipulating the valves may 70 be readily reached by the engineer or fireman of the locomotive.

While I have in the present disclosure shown the device as applied to a locomotive boiler, this is only by way of illustration, 75 as broadly it is adaptable for any type of boiler, stationary or otherwise, and the invention is therefore not to be considered as restricted in this particular.

8 designates bolts or like fastening means 80 by which the head is fixedly mounted upon the fire box sheet, the said fastenings engaging suitable lugs 9 on the bottom of the head or casing.

10 designates strut or brace members extending transversely of the head or casing 85 and serving to strengthen and reinforce the top and bottom portions thereof.

The head or casing 1 serves as an auxiliary steam chest or manifold member from 90 which steam may be delivered to any one of a number of points or to all of the points simultaneously according to requirements. In the present instance I employ the distributing head as a steam receptacle common 95 to a plurality of points of use, thus, for example, the steam from the head may be delivered independently to the steam injector, the air pump, the train pipe line, the feed water heater or to any other desired 100 portion of the engine mechanism, or it may be delivered simultaneously to all. I have,

therefore, for convenience, indicated the several delivery pipes from the head by the reference numeral 11, and each of these pipes is controlled by a valve mechanism which embodies an important feature of my invention. Since all of these valve members are identical in construction a description of one will suffice for all and I shall, therefore, apply the same reference characters to all of the valves and it will be understood that the respective parts are of duplicate construction.

12 designates a bushing screw-threaded into a suitable opening in the distributing head and having an exterior flange 13 which is adapted to seat in the counterbored portion of the head aperture where it contacts with a gasket 14 to prevent leakage at the joint. This bushing is provided with a 15 through port 15, the sides of which are preferably outwardly diverged and terminate in a threaded portion 16 to receive the pipe 11. The end of the bushing 12 which terminates within the head is provided with a valve seat 17 upon which the valve piece 18 is adapted to seat, the said valve piece having its stem 19 freely movable within an opening 20 of a lever arm 21. The lever arm 21, as here shown, is provided with openings 22 in each of which is a spring 23 for the purpose of contacting with the rear side of the valve piece 18 to hold the latter outwardly pressed and firmly seated upon the seat 17. The lever arm 21 is adapted to be oscillated to open and close the port 15, and a stop 23 is provided to limit the movement of the lever within a given range.

24 designates a spindle having an end to 40 receive the lever arm 21 and by which the latter is operated. As here shown the spindle 24 passes through the bushing 12 and the latter is suitably counterbored at each end for the following purposes. At the inner side of the bushing the spindle 24 is provided with a collar 25 adapted to seat against a packing ring 26 in the counterbored portion of the bushing, while the opposite counterbored portion receives a spring 45 27 which encircles the spindle 24 and bears against the sleeve 28, this latter being pinned to the spindle 24 by the pin 29 which also connects the crank operating member 30 thereto. By this construction the spindle 50 24 is held firmly seated at its inner end upon the bushing and prevents leakage of steam. The crank 30 is on the outer side of the bushing and is connected to the control lever 31, which may be carried to any convenient point for operation and preferably terminates in a handle such as 32. In the preferred embodiment of the invention I have shown a number of these control levers passing to the engineer's side of the engine cab 55 where they are all suitably grouped and

mounted for sliding movement in a plate or bracket 33. A similar construction is shown at 34 where a number of the control levers are carried adjacent the position ordinarily occupied by the fireman. In the drawings the control levers are shown arranged in a simple and orderly manner, but it will be understood that this is only by way of example, since in practice the levers are grouped according to conditions within the cab, such as the arrangement of the piping, gages or other fixtures, and it is therefore not always possible to carry the control levers to the points of use in the exact manner shown by these drawings.

80 In the operation of the distributing head and valve mechanism the main control valve 5 is normally open to admit steam from the boiler into the head, and therefore by opening any of the valve members the steam may be delivered directly to the point of use by way of the pipe or pipes 11. The respective valves are opened by shifting the proper control lever 31 so that the arm 21 which carries the valve piece is swung to one side 85 of the port opening, thereby allowing the free passage of steam. It will further be noted, in closed position of the arm 21, that the valve piece is firmly pressed to its seat by the springs 23. Preferably the bushings 90 which carry the valve parts are each provided with a polygonal head 35 so that they may be readily removed or operated by a wrench or like implement. In the modification shown in Fig. 5 I have provided the 95 bushing with suitable holes 36 so that a spanner wrench may be employed to actuate the bushings.

Attention is particularly directed to the fact that each valve and its operating adjuncts are carried by the bushing member 12 and consequently the parts are readily accessible for repair or replacement since any one of the bushings may be quickly and expeditiously removed from the distributing 100 head, thereby removing the valve parts also so that the parts may be interchanged, ground, adjusted, repaired or replaced. Of course it will be understood that this repair work on any or all of the valve members 105 is rendered effective by closing the main valve 5 and cutting off the supply of steam to the head 1. It will further be apparent by reason of the shape of the head that it may be readily placed in position upon substantially all types of locomotive or other boilers in present day use, and occupies little space while bringing all of the control levers into convenient range of the engineer, fireman or other occupant.

110 While I have shown my invention in the form which I have found particularly advantageous in commercial practice, I do not restrict myself to the details thereof as these may be modified or varied in many 115

ways without departing from the essential features of the improvement. For example, the particular shape of the distributor head is shown of that form which will give the most available top and lateral surfaces through which to provide properly directed openings for attaching the valve device, but it is manifest that this shape may be considerably varied; similarly, I have shown a compact form of valve device adapted to the openings of the distributor head, and while it is especially desirable to my improvements that the body parts of these valve devices which fit the openings shall provide the port and carry the entire valve mechanism so that the same may be removed as a unit from the head, nevertheless I do not restrict myself to the minor details as to the manner shown for journaling the spindle, nor of connecting the valve piece with the swinging arm, as these details may be modified without departing from the spirit of the invention. The essential feature of my improvement comprises the employment of a distributor head from which the steam may be supplied to the various pipes leading to the different places of the locomotive where steam is necessary for operating mechanisms or means, including pumps, injectors, etc., combined with a plurality of separate self-contained valve devices which are detachably secured in or to openings in the walls of the head, and means extending from said separate valve devices whereby any valve device may be operated by the engineer or fireman from a distance, the separate valve devices being independently removable for repair or other purpose, and moreover in which each valve device may be a complete operative element capable of being perfectly adjusted in the shop separate and distinct from its assemblage with the distributor head, whereby the apparatus, as a whole, may be kept in constantly operative condition and may be quickly repaired so as not to put the locomotive as a whole out of commission more than a nominal period of time should any such repairs be required.

Having thus described my invention, I claim and desire to protect by Letters Patent of the United States:—

1. In a device of the character stated, the combination of a boiler, with a steam box-shaped distributing head arranged upon the boiler above the fire-box end and provided with a plurality of openings, a conduit opening at one end into said head and at the other end into the steam space of a boiler, a valve device to control steam passing through the conduit, a plurality of bushings each removably secured in a different one of said openings, each of said bushings having a port therethrough, a valve carried by each bushing for controlling the port and

removable with the bushing, means carried by the bushings for controlling the opening and closing of the respective valves and also removable with the bushing, and separate operating means leading to a distance for independently actuating the several controlling means.

2. In a device of the character stated, the combination of a steam boiler, with a steam distributing head provided with a plurality of openings mounted upon the upper part of the boiler, a valve controlled conduit connecting said head with the steam space of said boiler, a bushing removably secured in each of said openings, said bushings each having a port therethrough, a valve carried by each bushing, means for controlling the opening and closing of the respective valves, and operating means exterior of said bushings and head for independently actuating the several controlling means.

3. In a device of the character stated, the combination of a steam boiler, with a steam distributing head provided with a plurality of openings mounted upon the steam boiler, a valve controlled conduit connecting said head with the steam space of said boiler, a bushing removably secured in each of said openings, said bushings each having a port therethrough, a valve seat on the inner face of each bushing, an arm mounted for swinging movement on each bushing and having a valve piece adapted to coact with the valve seat to open and close the port, a spindle secured to said arm and journaled in and extending through said bushing, and means exterior of said head and bushing and connected to the respective spindles for independently actuating the several valve pieces.

4. In a device of the character stated, the combination of a steam boiler, a steam distributing head provided with a plurality of openings mounted upon the boiler, a conduit connecting said head with the steam space of said boiler, a separate bushing removably secured in each of said openings, said bushings each having a port therethrough and a valve seat on the inner face of each bushing, an arm mounted for swinging movement on each bushing having a valve piece adapted to coact with the valve seat to open and close the port, means for holding said valve pieces pressed against their respective seats, a spindle journaled in each bushing for operating the valve, and separate means exterior of said bushing and head and connected to the respective spindles for independently actuating the several valve pieces from a distance.

5. In a device of the character stated, the combination of a steam boiler, a steam distributing head provided with a plurality of openings mounted upon said boiler, a conduit connecting said head with the steam space of said boiler, a bushing removably

secured in each of said openings and having a port therethrough and a valve seat on the inner face of said bushing, an arm mounted for swinging movement at the inner end of said bushing, a valve piece carried by said arm and adapted to coact with said valve seat to open and close said port, and means exterior of said bushing and head and extending through the bushing and connected 10 to said arm for operating it.

6. In a device of the character stated, the combination of a steam boiler, a distributing head provided with a plurality of openings mounted upon said boiler, said head having 15 communication with the steam space of said boiler, a separate bushing removably secured in each of said openings and having a port therethrough, an arm mounted at the inner end of each bushing for swinging 20 movement relatively to the port, a valve piece carried by said arm and adapted to open and close said port, a spindle extending through said bushing and connected to and supporting said arm, said spindle having 25 an annular bearing against the inner face of said bushing, means yieldingly holding said spindle to press the bearing into operative position to prevent leakage, and means exterior of said head and connected 30 to said spindle for operating said arm and valve piece.

7. In a device of the character stated, the combination of a steam boiler, a distributor head having top and peripheral walls and 35 providing communication with the steam space of the boiler, said head having a plurality of openings through its peripheral walls, self-contained valve devices tightly fitting the openings in the peripheral walls 40 and each comprising a removable body part having a steam port therethrough and providing a valve seat on the inner surface about said port, a pivoted spindle journaled in the body part and having a swinging arm 45 on its inner end carrying a valve piece working on the valve seat for controlling the port, and separate means for operating the valve spindles extending to a distance whereby the engineer may from said distant 50 place operate either valve desired.

8. In a device of the character stated, the combination of a steam boiler, a distributor head having top and side walls and providing communication with the steam space of 55 the boiler said head having a plurality of openings through its top and side walls, self-contained valve devices tightly fitting the openings in said walls and each comprising a removable body part having a steam port therethrough and providing a valve seat on the inner surface about said port, a pivoted spindle journaled in the body part and having a swinging arm on its inner end carrying 60 a valve piece working on the valve seat

for controlling the port, and separate means 65 for operating the valve spindles extending to a distance and terminating in assembled arrangement whereby the engineer may from said distant place operate either valve desired without looking at or reaching for 70 the valves.

9. In a device of the character described, a steam boiler, combined with a distributor head having communication with the steam space of the boiler and provided with a plurality of openings through its walls, a plurality of independent valve devices each detachably fitting one of said openings in the head and comprising a body part having a valve seat upon its inner surface and a port 75 opening through said seat, a rocking spindle journaled in the body portion to one side of the port, an arm secured to the inner end of the spindle and provided with a valve piece working upon the valve seat to control the 80 port, means on the body portion for holding the spindle against longitudinal inward movement, and separate means extending to a distance for operating each of the spindles of the respective valve devices whereby the 85 engineer may operate any valve desired from a distance and said valve devices may be separately removed with all of the associated operative parts.

10. In a device of the character stated, the combination of a steam boiler, with a steam distributing head having communication with the steam space in the boiler and provided with a plurality of openings through its walls, a separate valve device detachably 100 secured in each of the openings, and each of said valve devices comprising a body part fitting the openings and provided upon its inner surface with a valve seat and a port extending through the body part therefrom, 105 a spindle extending through the body part and journaled therein to form a steam tight joint, an arm secured upon the inner end of the spindle, a valve piece loosely carried by the free end of the arm, spring devices 110 for pressing the valve piece upon its seat, and a separate operating means extending from each of the spindles of the respective valve devices to a distance whereby the engineer may operate either valve desired from 115 the distant place.

11. In an apparatus of the character stated, a steam boiler, combined with a steam distributing head mounted thereon and having a plurality of openings through its 120 walls, a steam controlled conduit for supplying steam to the head from the steam space of the boiler, and a separate valve device for each of the openings in the head, each of said valve devices comprising a body 125 part detachably connected in one of the openings of the head and having a steam port therethrough and provided with port con-

trolling means, and means wholly supported and carried by the body part and extending to the outside thereof for operating the port controlling means whereby each port controlling means is in association with its seat and independent and removable relative to the other valve devices.

In testimony of which invention, I hereunto set my hand.

SAMUEL S. RIEGEL.
